UNITED STATES PATENT OFFICE.

EDWARD FERGUSON CHAUCE, OF WEST SMETHWICK, COUNTY OF STAFFORD, ENGLAND.

DESIGN FOR THE ORNAMENTATION OF GLASS.

SPECIFICATION forming part of Design No. 19,707, dated March 18, 1890.

Application filed February 11, 1890. Serial No. 340,038. Term of patent 14 years. Registered in England January 26, 1889, Nos. 118,358 and 118,359.

To all whom it may concern:

Be it known that I, EDWARD FERGUSON CHAUCE, managing director of Chauce Brothers & Co., (Limited,) glass-manufacturers, a subject of the Queen of England, residing at West Smethwick, in the county of Stafford, England, have invented and produced a new and original Design for the Surface Ornamentation of Glass, (which design has been registered in Great Britain, January 26, 1889, Nos. 118,358 and 118,359,) of which the following is a specification, reference being had to the accompanying drawings, forming part hereof.

5 The design is for the surface ornamentation of glass; and, as represented in the drawings, Figure 1, it consists of a series of squares A, divided by intersecting lines *a* *in intaglio*, each square being itself composed of four smaller

squares *a'*, having triangles *a²* *in intaglio*, the same being separated by camaieu lines *a³*. In Fig. 2 the triangles *a²* are camaieu-like or *in rilievo*, being separated by lines *a³* *in intaglio*. This ornamentation is made throughout the entire surface of the glass, as shown in Fig. 1, or in large squares in the center thereof, as seen in Fig. 2.

I claim—

The design for the surface ornamentation of glass, substantially as herein shown and described.

In testimony whereof I affix my signature in presence of two witnesses.

EDWARD FERGUSON CHAUCE.

Witnesses:

GEORGE SHAW,
RICHARD SKERRETT.
